UNITED STATES PATENT OFFICE.

ROBERT MCKAY, OF DETROIT, MICHIGAN.

DESIGN FOR A HEEL.

SPECIFICATION forming part of Design No. 30,040, dated January 17, 1898.

Application filed December 21, 1898. Serial No. 699,961. Term of patent 14 years.

To all whom it may concern:

Be it known that I, ROBERT MCKAY, a citizen of the United States, residing at Detroit, in the county of Wayne and State of Michigan, have invented and produced a new and original Design for a Heel, of which the following is a specification, reference being had therein to the accompanying drawings, in which—

10 Figure 1 is a plan. Fig. 2 is a side elevation, and Fig. 3 is a perspective view.

A is a flat body having an oval or elliptic contour B, extending around the back and sides and a slightly-concaved front C.

15 D are circular bosses arranged around the oval or elliptic contour and forming a horseshoe appearance.

E are central round holes in the bosses, and F are similar holes arranged along the concave front.

The leading feature of my design is the row of bosses arranged in horseshoe shape around the front and sides of the plate.

What I claim as my invention is—

The design for a heel as herein described and shown.

In testimony whereof I affix my signature in presence of two witnesses.

ROBERT MCKAY.
